Specification for Design.

Patented Sept. 14, 1920.

Application filed October 24, 1919. Serial No. 333,131. Term of patent 14 years.

To all whom it may concern:

Be it known that I, JOHN C. McLEAN, a citizen of the United States, residing at Lakewood, in the county of Cuyahoga and State of Ohio, have invented a new, original, and ornamental Design for a Tire-Tread, of which the following is a specification, reference being had to the accompanying drawing, forming a part thereof.

In said drawing, Figure 1 is a transverse sectional view on line 1—1 of Fig. 2; Fig. 2 is a top plan view of my tire tread; Fig. 3 is a sectional view on line 3—3 of Fig. 2.

I claim:

The ornamental design for a tire tread substantially as shown.

JOHN C. McLEAN.
